DESIGN FOR AN EXTENSION OIL DRAIN OR SIMILAR ARTICLE

Willard C. Moore, Dayton, Ohio

Application September 20, 1946, Serial No. 133,453

Term of patent 3½ years

(Cl. D52—2)

To all whom it may concern:

Be it known that I, Willard C. Moore, a citizen of the United States, residing at Dayton, in the county of Montgomery and State of Ohio, have invented a new, original, and ornamental Design for an Extension Oil Drain or Similar Article, of which the following is a specification, reference being had to the accompanying drawing, forming a part thereof.

Figure 1 is a perspective view of an extension oil drain or similar article, showing my new design.

Figure 2 is a top plan view thereof.

Figure 3 is a side elevational view.

Figure 4 is an end elevational view.

The essential features of my design reside in the portion shown in full lines.

I claim:

The ornamental design for an extension oil drain or similar article, as shown and described.

WILLARD C. MOORE.
